UNITED STATES PATENT OFFICE.

ALBERT H. BIEN, OF PHILADELPHIA, PENNSYLVANIA.

DESIGN FOR A TEXTILE FABRIC OR SIMILAR ARTICLE OF MANUFACTURE.

Application filed April 5, 1928. Serial No. 26,135. Term of patent 14 years.

To all whom it may concern:

Be it known that I, ALBERT H. BIEN, a citizen of the United States, residing in Philadelphia, Pennsylvania, have invented a certain new, original, and ornamental Design for Textile Fabric or Similar Article of Manufacture, of which the following is a specification, reference being had to the accompanying drawing, forming part thereof, the figure of which is a face view of textile fabric or similar article of manufacture, illustrating my new design; the arrows thereon indicating the complete unit of the design.

I claim:

The ornamental design for textile fabric or similar article of manufacture, substantially as shown and described.

ALBERT H. BIEN.
